TENSION-CONTROLLING MECHANISM FOR SEWING-MACHINES.

1,346,103.

Specification of Letters Patent. Patented July 13, 1920.

Original application filed February 16, 1918. Serial No. 217,483. Divided and this application filed August 16, 1919. Serial No. 317,903.

To all whom it may concern:

Be it known that I, EDWARD B. ALLEN, a citizen of the United States, residing at

Newtown, in the county of Fairfield and

5 State of Connecticut, have invented certain new and useful Improvements in Tension-Controlling Mechanisms for Sewing-Machines, of which the following is a specification, reference being had therein to the accompanying drawings.

10 The present invention, which has been divided out of my copending application Serial No. 217,483, filed February 16, 1918, has for an object to provide an automatic

15 sewing machine, more particularly of the buttonhole type, with improved mechanism which will act automatically and in a positive manner to release the tension at the end of the stitching cycle, preferably after

20 the stitch-forming mechanism has come to rest.

A further object of the invention is to provide an improved mechanism for effecting the restoration of the tension prior to

25 the next stitching operation.

A more general object of the invention is to provide a cam and follower mechanism wherein the cam operates normally to shift the follower away from an initial position, 30 with means whereby the follower may be restored to initial position while the cam is stationary.

A further object of the invention is to provide a cam and follower mechanism wherein the cam normally actuates the follower, 35 with means for moving the follower along the cam to alter the time at which the follower would be actuated by the cam if the motion of the latter alone were depended

40 upon.

Still further the invention has for an object to provide a cam actuated mechanism suitable for operating various sewing machine thread-handling devices such as pull-offs, tensions, thread-cutters, and the like, 45 which it may be desirable to operate at different periods of the stitching operation.

To the attainment of the above and other objects, as will hereinafter appear, I have 50 embodied the invention in an automatic buttonhole cutting and stitching machine and have combined with the stitch-forming mechanism and with the usual cutter-shaft which is driven independently of the stitch-

forming mechanism and performs a single 55 rotation at one stage of the buttonhole-producing cycle, a second auxiliary shaft which is also driven independently of the stitch-forming mechanism and is caused to perform in a positive manner the various operations during another stage of the buttonhole-producing cycle. Preferably, this second auxiliary shaft is controlled through an automatic clutch permitting it to perform a single rotation only; the clutch being tripped into action preferably by the stop-motion device for the stitch-forming mechanism at the end of the stitching or second stage of the buttonhole-producing cycle so that the second auxiliary shaft will 70 perform its function or functions only during the third or final stage of the buttonhole-producing cycle.

The second auxiliary shaft is provided, in the present machine, with a cam which acts 75 through a follower and suitable connections to release the tension, trip the thread-cutter and open the work-clamps in a predetermined order and at properly spaced time intervals.

Suitable connections with the stop mechanism serve to shift the cam-follower peripherally of the tension-releasing cam to effect the restoration of the tension at the beginning of the next sewing operation,

The gist of the invention, in its broader aspects, is the provision of cam-and-follower mechanism, wherein the cam moves at times to shift the follower, with a follower shifting means which may be operated to 90 move the follower along the cam whereby the time of actuation of the follower is not solely dependent upon movement of the cam.

In the accompanying drawings, Figure 1 95 is a side elevation of the machine, partly in section. Fig. 2 is a rear elevation of the machine. Fig. 3 is a plan view, partly in section, showing the feed-wheel, the two auxiliary shafts and the mechanism associated therewith. Fig. 4 is a view in elevation of the feed-wheel and the crank mechanism for turning the latter at one stage of the cycle and Fig. 5 is a detail perspective view of said crank mechanism. Figs. 6, 7 105 and 8 are detail perspective views of the clutch-controlling mechanism for the auxiliary shaft shown in Figs. 4 and 5. Figs.

9 and 10 illustrate details of the clutch-controlling mechanism in elevation. Fig. 11 is a view of the cam and follower which control the tension-releasing, thread-cutting and clamp-opening operations.

In the particular embodiment of the invention chosen for the purposes of the present disclosure, the machine frame comprises the hollow rectangular base 1 formed with a bed-plate 2 from the rear end of which rises the hollow standard 3 carrying the usual bracket-arm 4 which terminates in the hollow head 5. Extending within and lengthwise of the base 1 is the main-shaft 6 for the stitch-forming mechanism. This shaft carries a bevel-gear 7 which meshes with a companion gear 8 of equal size fixed to the lower end of the vertical shaft 9 journaled within the standard 3. The vertical shaft 9 acts through one-to-two speed multiplying bevel-gears 10 to drive the needle-bar actuating shaft 11 which at its forward end is connected to the reciprocating needle-bar 12 by means of the usual crank 13 and link 14. The stitch-forming mechanism of the machine may be of any suitable type. In the present instance it is constructed substantially in accordance with the disclosure of my Patent No. 1,162,207, of November 30, 1915, and embodies the reciprocating straight needle 15 carried by the needle-bar 12 and the lower curved needle 16 which is sustained in the turret 17.

Mounted beneath the bed-plate 2 on the screw-pin 18 is the well-known feed-wheel 19 which is formed in its under face with a cam-groove, not shown, acting during a partial rotation of the feed-wheel to shift the cam-follower 21, Fig. 3, and through the usual connections therewith, to turn the stitch-forming mechanism while stitching around the eyelet-end of a buttonhole. At the end of the stitching operation the feed-wheel is given a further turning movement to complete its single rotation and at this time acts to turn the stitch-forming mechanism back to initial position. The cam-follower 21 is sustained by a lever-arm 22 fixed at one end to the vertical fulcrum-shaft 23 and at its opposite end connected by means of the link 24 to the bellcrank-lever 25 which carries the usual toothed sector-gear 25' meshing with a pinion 25'', Fig. 1, on the turret 17. The vertical fulcrum-shaft 23 carries a crank-arm 26 which is connected by means of a link 27 to a bellcrank-lever 28 formed with the toothed sector-gear 29 meshing with the pinion 30 connected to the bushing 31 from which depends the guide-arm 32 having a channelway entered by a stud 33 on the needle-bar, all as more fully described in my said Patent No. 1,162,207.

The buttonhole cutting mechanism of the machine is preferably constructed in substantial accordance with the disclosure of

my Patent No. 1,048,786, of December 31, 1912, and comprises the usual upper and lower cutter-levers 34 and 35 which are advanced and closed to cut the buttonhole-slit in stitching position by means of the usual 70 connections with the cutter-closing cams 36, 36' and the cutter-advancing and retracting cam 37, all carried by the cutter-shaft 38 which is driven independently of the stitch-forming mechanism from a constantly running pulley 39 through the well-known automatic single-rotation clutch mechanism 40 fully disclosed in my said Patent No. 1,048,786. When the cutter-shaft controlling clutch is tripped into action during the 80 first stage of a buttonhole-producing cycle the constantly running driving pulley imparts a single complete revolution to the cutter-shaft, as is well understood.

The work-holder of the present machine is 85 constructed substantially in accordance with the disclosure of my copending application Serial No. 180,737, filed July 16, 1917, and comprises upper and lower work-clamping elements 41 and 42, of which the upper are 90 carried at the forward ends of the clamp-arms, one of which is shown at 44.

The main-shaft 6 of the stitch-forming mechanism is controlled by means of a suitable stop-motion device preferably such as 95 disclosed in my said Patent No. 1,048,786. A stop-motion device of this type embodies a tilting starting and stopping lever 45 which is fixed to a fulcrum-pin 46 journaled in the bearing lugs 47. The lever 45 is urged to 100 stopping position by the spring 48 and is held in running position, Figs. 1 and 2, by means of the latch 49, the upper extremity of which engages over a wear plate 50 on the arm 51 fixed to and extending forwardly 105 from the fulcrum-pin 46. The arm 51 carries a cam-roll 52 at its free end which is depressed by a cam 53 on the cutter-shaft 38 to start the stitch-forming mechanism during the latter part of the single rotation of 110 the cutter-shaft. At the completion of the stitching operation a tripping point 54 on the feed-wheel acts through a lever 55 to displace the latch 49 laterally and release the lever-arm 51 thereby permitting the stop-lever 45 to spring to stopping position.

As is well understood by those skilled in the art, stop-motions of the present type embody a downwardly spring-pressed slide-block 56 which is mounted upon the stop-lever 45 and is formed with a tooth 57 which snaps into position over the peripheral surface 58 of the clutch-ring 59 when the stop-lever swings to stopping position. Further turning movement of the main-shaft causes 120 the slide-block 56 to be lifted as the outwardly inclined cam-portion 60 of the clutch-ring rides under the tooth 57. Finally, the tooth 57 drops into the stop-notch 61 in the clutch-ring, as the abrupt shoulder 62 form- 125 130

ing one side wall of said notch strikes the side face of the tooth 57 and arrests the motion of the main-shaft. This well known upward and downward movement of the slide-block 56 is utilized in the present machine for a purpose to be hereinafter described.

The present machine embodies, in combination with the foregoing features of construction, a second auxiliary shaft 63 which 5 is journaled within and transversely of the bed 1 in the bearings 64 and 65, Fig. 3, and, in the present instance, is utilized to release the tension subsequent to stitching. This shaft is normally stationary during the 10 stitching operation and is caused to perform preferably a single revolution only during the third or last stage of the buttonhole-producing cycle. Mounted to turn freely upon an outboard projection of the shaft 63 is 15 the constantly rotating driving disk 66 of an automatic one-revolution clutch device. One side face of the disk 66 is recessed to form a peripheral flange 67 into which is let a series of peripherally spaced and in- 20 wardly directed driving teeth 68. The driving disk 66 is further formed with a hub 69 integral with which is a gear-wheel 70 meshing with a pinion 71 fixed to the well-known belt-wheel 39 which turns freely 25 upon the first auxiliary or cutter-shaft 38. The arrangement of the auxiliary shafts 38 and 63 in parallelism transversely of the machine bed and the gear connected driving disks concentric therewith are features of 30 construction which make for a simple, compact and efficient auxiliary mechanism adapted to be driven from a single belt-wheel at the side of the machine and which may be utilized to perform any or all of the 35 various operations before and after stitching.

Fixed to the second auxiliary shaft 63 adjacent the driving disk 66 is a driven disk 72 formed with a radial slideway 73 in 40 which is fitted a slide-block 74 having at one side a clutch-tooth 75 which projects laterally into the recessed portion of the driving disk. At its opposite side the slide-block 74 is formed with a stopping tooth 76 45 which projects through the slot 77 in the face of the driven disk 72 remote from the driving disk. A spring 78, Fig. 6, mounted on the disk 72 and having its free end bearing against the notched inner end of the 50 clutch-tooth 75 is utilized to urge the slide-block 74 outwardly, thereby projecting the clutch-tooth 75 to a position wherein it will be struck by one of the driving teeth 68, thus 55 coupling the shaft 63 to the source of power. 60 Fulcrumed on the screw-pin 79 is a clutch-controlling bellcrank-lever having a depending arm 80 which at its lower extremity carries an abutment block 81 having an inclined cam face 82, a detaining shoulder 83 65 and a stop-shoulder 84. Pivoted to the arm

80 at 85 is a spring-pressed latch 86 the lower extremity of which is spaced above the stop-shoulder 84. The other arm 87 of the clutch-controlling bellcrank-lever is pulled downwardly by the coil spring 88 which 70 acts yieldingly to hold the abutment block 81 in a position such that the stopping tooth 76 is detained in its retracted position by the detaining shoulder 83 and is locked against upward or downward displacement 75 by the latch 86 and stop-shoulder 84, respectively.

In the normal stopping position of the parts thus described, the slide-block 74 is at its extreme inner position with the clutch-tooth 75 withdrawn from engagement with the clutch-teeth 68 of the driving disk 66. The shifting of the clutch-controlling bellcrank-lever, by means presently to be described, so as to move the arm 80 away from 80 the adjacent face of the driving disk 66, disengages the stop-shoulder 84 and detaining shoulder 83 from the stopping tooth 76 of the slide-block 74, thus permitting the latter to move outwardly under the action of its 85 spring 78 to introduce the clutch-tooth 75 into engagement with one of the driving teeth 68. As the driven disk 72 nears the completion of a single revolution, the clutch-controlling bellcrank-lever has been 90 returned to initial position by the action of both the spring 88 and the more positive action of the inclined face 89 of the cam-rib 90 upon the bent extremity 91 of a lateral arm 92 secured to the lower end of the 95 clutch-controlling lever-arm 80, thus bringing the cam face 82 of the abutment block 81 into the path of movement of the stopping tooth 76 by means of which the slide-block 74 is thrust inwardly to disengage its 100 clutch-tooth 75 from the driving teeth 68. As the stopping tooth 76 arrives at initial position, it engages the stop-shoulder 84 and is prevented from rebounding by the extremity of the latch 86 which snaps into 105 operative position as the stopping tooth 76 passes it. By the means thus described, the second auxiliary shaft 63 is insured a single 110 complete revolution for each clutch-releasing actuation of the controlling bellcrank-lever 80, 87.

The second auxiliary shaft 63 is formed between its ends with a bellcrank 93 which operates through the pitman 94, as described in the parent application, to quickly 115 restore the feed-wheel to initial position during the final stitch of the buttonhole-producing cycle.

It will be noted that in the normally stationary position of the second auxiliary 120 shaft 63, Fig. 4, the crank 93 is slightly above its rearward dead-center position. In this figure the stop-motion lever 46 has just been tripped and the main-shaft 6 has yet to turn a part of a revolution to first ele- 125

vate the stopping tooth 57 and then permit it to snap into the stop-notch 61 of the clutch-ring 59.

The slide-block 56 carrying the stopping tooth 57 is connected by a link 95 to the rearwardly extending arm of a lever 96 pivoted to the frame by the screw-pin 97. Pivoted to the forwardly extending arm of the lever 96 is a spring-pressed latch 98, Figs. 3 and 8, the extremity of which is adapted to snap under the lateral arm 87 of the bellcrank clutch-controlling lever when the slide-block 56 is lifted by the eccentric surface portion 69 of the clutch-ring 59. When the stopping tooth 57 snaps into the stop-notch 61, the slide-block 56, in falling, acts through the link 95, lever 96 and latch 98 to lift the arm 87 and thereby retract the depending arm 80 of the bellcrank clutch-controlling lever and effect the coupling of the auxiliary shaft 63 to the driving disk 66 for a single revolution.

Pivoted to the frame at 99 is an upstanding lever 100 the upper free end of which is yieldingly held against a stop-screw 101 by the action of the spring 88 which is connected at its lower end to a lateral arm 102 of said lever. The lever 100 carries a laterally projecting cam-block 103 having an inclined face 104 which lies in the path of downward movement of the crank-arm 105 and is deflected to one side as the crank-arm passes it during the first part of its single revolution, as shown in Figs. 2 and 5. When the lever 100 is deflected, its upper end strikes the latch 98 and disengages it from the arm 87 of the bellcrank clutch-controlling lever, thereby allowing said lever to immediately return to clutch-disengaging position under the action of the spring 88 or under the more positive action of the cam surface 89 of the clutch-wheel 72 upon the bent extremity 91 of the lateral arm 92 fixed to said clutch-controlling lever.

The second auxiliary shaft 63, with which the present machine has been provided, may be utilized in the performance of various operations during the final stage of a buttonhole producing cycle. For example, the shaft 63 has, in the present instance, been provided with a cam-member 106 in the form of a pair of spaced disks of similar shape between which is guided the lower end of a lifting bar 107 the upper end of which is pivotally connected to the rearward end of the tension releasing lever 108 fulcrumed to the bracket-arm 4 at 109. At its down-turned forward end the tension-releasing lever is formed with a lateral recess 110 affording an inclined cam-wall serving when moved downwardly to shift the usual tension-releasing pin 111 inwardly to separate the spring-pressed disks of the tension device 112 for the needle-thread.

Projecting rearwardly from the lifting

bar 107, intermediate the ends of the latter, is an arm 113 having at its free end a vertical slot 114 loosely entered by a screw-pin 115 which is threaded into the lower extremity of the hand-lever 116 pivotally secured to a boss 117 formed at the upper extremity of the stop-motion lever 45. The inner end of the screw-pin 115 projects some distance laterally of the hand-lever 116 and is yieldingly held in engagement with the stop-motion lever 45, Fig. 3, by means of the spring 118 which is coiled about the boss 117 and one end of which is hooked about the hand-lever 116, Figs. 1 and 2, and tends to pull the upper end of said hand-lever forwardly. The lifting bar 107 is formed at its lower end with a laterally projecting follower lug 119 adapted to bear upon the peripheral portion of one of the cam-disks 106.

Pivotedly mounted on the bed 1 at 120 is the rearward end of the lever-arm 121 which is yieldingly depressed by the forward extension 122 of a leaf-spring 123 screwed to the bed 1. The upwardly and inwardly extending forward extremity 124 of the lever-arm 121 overhangs the bed 1 in a position directly beneath the rearward extremity of the latch-lever 125 which locks the work-clamps in closed position. A lever 125^x is adjustably fixed to the lever-arm 121 by means of the pivot-screw 126 and the screw 127 which enters a slot 125' in the forward extremity of said lever 125^x and is threaded into the lever-arm 121. Extending upwardly and inwardly from the lever 125^x into overhanging relation with the bed 1 is an arm 128 which is positioned under the tail of the latch-lever 129 for the thread-cutter rod 130, as described in the parent application.

The rearwardly extending arm of the lever 125^x is adapted to be depressed to elevate the cutter and work-clamp tripping extension 124, 128, by means of the lever 129^x which is pivoted to the standard 3 at 130^x and the laterally bent rearward arm 131 of which enters the horizontal slot 132, Fig. 1, in the lifting bar 107. The two arms of the lever 129^x are relatively adjustable, one of them being formed with a slot 133 which is entered by a screw 134 threaded into the other.

The foregoing parts are so adjusted that when the lifting bar 107 is elevated it first acts to release the tension, second to trip the thread-cutter and lastly to open the work-clamps. To secure the proper spacing of these operations in point of time, the cam 106 is formed with a tension releasing rise 135, Fig. 11, which merges into a cutter tripping rise 136 the latter being followed by a dwell 137 which merges into the clamp-opening rise 138. Following the clamp-opening rise is a depression 139 which permits the cutter- and clamp-opening ex-

130

tensions 124 and 128 to drop sufficiently to insure that the work-clamps may be closed and the cutter reset, but not enough to restore the tension on the needle-thread. Following the depression 139 is a long concentric portion or dwell 140 extending substantially three-fourths of the distance around the cam and terminating in an abrupt declivity 141.

- 10 Prior to the starting of the machine, the cam-follower lug 119 rests upon the end of the concentric portion or dwell 140 of the cam, as shown in full lines in Fig. 11. When the stop-lever 45 is tilted to starting position by the action of the usual cam 53 on the cutter-shaft, the lower end of the lifting bar 107 is shifted forwardly, or peripherally of the cam 106 by the action of the screw-pin 115 carried by the stop-motion lever, and the follower lug 119 drops over the declivity 141 and moves substantially radially of the cam 106 to the position shown in dotted lines in Fig. 11; the cam 106 thus permitting the spring 142 to effect the downward motion of the lifting bar 107 and the consequent restoration of said bar 107 and the follower 119 to initial position, thereby effecting restoration of the thread-tension as the notch 110 of the lever 108 is brought 25 into register with the tension-releasing pin 111.

In the operation of the present machine which embodies the invention in its preferred form, the work is placed in position under the raised clamping feet and the machine is started by the usual treadle-device, not shown, which trips the cutter-shaft into action. During the single revolution of the cutter-shaft, the work-clamps are closed, the 35 buttonhole-slit is cut and spread and the stop-lever 45 is tilted to running position, Fig. 1, by the action of the cam 53 on the cam-roll 52 at the free end of the lever-arm 51; the latch 49 snapping over the lever-arm 51 and holding the stop-motion lever in running position. The tension on the needle-thread is restored when the cam-follower lug 119 is pushed over the declivity 141 by the tilting of the stop-motion lever.

- 50 As the stitching progresses, the feed-wheel 19 receives a relatively slow step-by-step turning motion through the usual gear connections with the star-wheel 143, Fig. 1, with which meshes the diametrically opposed pins 144 carried by the lower end of the vertical shaft 9. In stitching around the eyelet-end of the buttonhole, the stitch-forming mechanism is given a turning movement through the usual connections 55 with the feed-wheel. When the buttonhole is completely stitched, the tripping point 54 strikes the lever 55 and effects the release of the arm 51 from the latch 49, thus permitting the stop-motion lever to spring to 60 stopping position.

The upward movement of the slide-block 56 carried by the stop-motion lever engages the latch extremity of the lever 96 under the lateral arm 87 of the bellcrank clutch-controlling lever for the second auxiliary shaft 63. As the stopping tooth 57 drops into the notch 61 of the clutch-ring 59 to stop the stitch-forming mechanism, the downward-moving slide-block 56 retracts the depending arm 80 of the bellcrank-lever, thus tripping the second auxiliary shaft 63 into action to perform its single revolution during which the tension is released, the thread-cutter is tripped, and the work-clamps are opened. The feed-wheel is also rapidly restored to initial position without noise or shock in the manner described in the parent application.

While I have disclosed the invention as embodied in a buttonhole sewing machine of a particular type, it is to be understood that the invention in many of its aspects is well adapted for use in any of the usual, automatic sewing machines having predetermined cycles of operation as well as in sewing machines generally.

Having thus set forth the nature of the invention, what I claim herein is—

1. In an automatic sewing machine, in combination, stitch-forming mechanism, a stop-motion therefor, a tension-device for the sewing thread, an auxiliary shaft normally stationary during the stitching operation and performing but a single rotation subsequent to the stitching operation, and means connected to said shaft for opening the tension device.

2. In an automatic sewing machine, in combination, stitch-forming mechanism, a stop-motion therefor, a tension-device for the sewing thread, an auxiliary shaft normally stationary during the stitching operation and performing but a single rotation subsequent to the stitching operation, means connected to said shaft for opening the tension-device and means connected with the stop-motion and co-operating with the auxiliary shaft while said shaft is stationary to automatically close the tension-device when the stitch-forming mechanism is started.

3. In an automatic sewing machine, stitch-forming mechanism, a stop-motion therefor, a tension device, a tension-controlling cam, a cam-follower connected to said tension device, means for turning said cam to release the tension subsequent to the stitching operation, and means for shifting said cam-follower peripherally of said cam while the latter is stationary to effect the restoration of the tension at the beginning of the next stitching operation.

4. In an automatic sewing machine, stitch-forming mechanism, a stop-motion therefor, a tension device, a tension-controlling cam, a cam-follower connected to said tension de-

vice, means for turning said cam to release the tension subsequent to the stitching operation, and means connected to said stop-motion for shifting said cam-follower peripherally of said cam while the latter is stationary to effect the restoration of the tension at the beginning of the next stitching operation.

5. In an automatic sewing machine, stitch-forming mechanism, a stop-motion therefor; a tension device, a tension-controlling cam having a tension-releasing cam-rise and a declivity, a cam-follower connected to said tension device, means for turning said cam to release the tension subsequent to the stitching operation, and means connected to said stop-motion for pushing said cam-follower over the declivity of said tension-controlling cam while the latter is stationary, 15 to effect the restoration of the tension prior to the next stitching operation.

6. In a sewing machine, an actuated element, a cam, and a cam-follower connected to said actuated element and adapted to be 20 acted upon by said cam, and means inde-

pendent of said cam for shifting the follower circumferentially thereof.

7. In a sewing machine, a cam, a cam-follower, means for moving the cam at one time to actuate the follower, and means for 30 shifting the follower along an active portion of said cam while the latter is stationary, whereby said active portion controls the movement of the follower at another time.

8. In a sewing machine, in combination, stitch-forming mechanism, a thread-engaging device, an actuating cam, a cam-follower connected to said thread-engaging device, means for turning said cam to control the 40 action of said thread-engaging device, and means for shifting said cam-follower peripherally of the cam over an active portion of the latter to effect the restoration of the thread-engaging device to initial position.

In testimony whereof, I have signed my name to this specification.

EDWARD B. ALLEN.
